UNITED STATES PATENT OFFICE.

DANIEL M. FRYE, JR., OF PHILADELPHIA, PENNSYLVANIA, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR LEVELING SPRING-HEEL SHOES.

1,271,694.

Specification of Letters Patent.

Patented July 9, 1918.

Application filed September 29, 1915. Serial No. 53,180.

To all whom it may concern:

Be it known that I, DANIEL M. FRYE, Jr., a citizen of the United States, residing at Philadelphia, in the county of Philadelphia and State of Pennsylvania, have invented 5 certain Improvements in Machines for Leveling Spring-Heel Shoes, of which the following description, in connection with the accompanying drawings, is a specification, 10 like reference characters on the drawings indicating like parts in the several figures.

The present invention relates to machines for leveling spring-heel shoes.

In the manufacture of spring-heel shoes, 15 as now commonly practised, the forepart and shank portions of the outersole are secured to the shoe by stitches, and the heel portion is then nailed to the heel seat. To give the desired rise or height to the heel, a 20 heel blank or wedge is placed between the inner surface of the heel portion of the outersole and the heel seat, and the metallic fastenings or nails are then driven through the outersole and the wedge along the edge 25 portions thereof and into the heel seat where they are usually clenched.

As the metallic fastenings or nails are driven into the heel, the lines of the crease, which define the space between the shoe upper and the edges of the wedge or outersole about the heel portion of the shoe, are liable 30 to be distorted and made irregular by the action of the driving means which inserts the fastenings or nails at intervals. This

35 irregularity in the lines of the crease is apparent along the edges of the wedge and outersole and while it is particularly pronounced in spring-heel shoes where the fastenings or nails are driven singly, as by the 40 loose nailer, it also manifests itself in spring-heels where the fastening or nails are driven in groups. A feature of the present invention, therefore, consists in a leveling means for spring-heel shoes wherein the top 45 edge portions of the wedge and outersole about the heel portion of the shoe are supported by a substantially rigid member and subjected to a leveling pressure exerted by it and a tread surface leveling member to 50 impart or restore to the edge portions of the wedge and outersole the straight and regular lines desired and an even surface to the tread face of the outersole.

At the break of the heel where the outer-

sole passes over the tapering portion of the 55 heel blank or wedge, difficulty is experienced in securing and maintaining during wear, a straight and sharply-defined incline leading from the tread surface of the heel to the shank. At this portion of the shoe one or 60 more nails are usually driven through the outersole into the incline of the wedge at each side. During wear, however, as in walking, the shoe is constantly being bent at this point and the nails at the incline or 65 corner nails, as they are commonly termed, are consequently subjected to great strain and stress in maintaining the parts in established relation. It is important, therefore, that these nails at the corners or incline of the heel be securely fastened, and the present invention contemplates that during the leveling action these nails be 70 securely clenched to the forward portion of the heel seat. Accordingly, the present 75 embodiment of the invention provides an incline leading from the flat leveling surface of the heel leveling plate corresponding to the desired incline of the outersole at the break of the heel which acts upon the 80 corner nails and insures a proper clench thereof to the heel seat during the leveling action.

Other features of the invention and novel combinations of parts comprised therein will 85 be hereinafter described and defined by the claims.

In the drawings:—

Figure 1 is a perspective view of a machine embodying the present invention, 90 many of the parts being omitted for clearness of illustration and as unnecessary for a proper disclosure of the invention;

Fig. 2 is a sectional detail showing the heel portion of a spring-heel shoe and the 95 position of the leveling means during the leveling operation;

Fig. 3 is a detail showing the support for supporting the top edges of the wedge and outersole of a spring-heel shoe during the 100 leveling operation;

Fig. 4 is a detached perspective detail view of the leveling plate;

Fig. 5 is a perspective view showing a spring-heel shoe after it has been treated in 105 accordance with the present invention; and

Fig. 6 is a perspective detail of a modified form of leveling plate.

In straightening the lines at the crease and leveling the tread surface of spring-heel shoes, in accordance with the present invention, the shoe is subjected to pressure between opposed pressure members which are relatively movable toward and from each other. The general character of the pressure members is such that the interior of the shoe and the exterior projecting edge 10 of the wedge and outersole about the heel portion of the shoe are supported while a leveling pressure is exerted upon said parts by relative movement of the pressure members. Such relative movement of the pressure members may be effected in various ways, either by a machine especially designed for this purpose, or by any of the well-known forms of machines for acting upon the heel portions of shoes, wherein the 20 shoe is subjected to pressure. In the latter case a machine of known type may have applied thereto and combined therewith, the pressure members of the present invention, and for the purpose of the present exploitation of the invention, a machine of the general character and organization of that described in Letters Patent of the United States, No. 694,656, dated March 4, 1902, is illustrated.

In this machine the frame 1, only a portion of which is shown, supports the various parts. The nail block head 2 carries the nail block 3 and is given reciprocating movement toward and from the jack 4 by means of the rods 5, the construction being such that a shoe placed upon the jack will be subjected to pressure between said jack and nail block when said parts are relatively moved, all as is more fully described 40 in the before-mentioned patent to which reference may be had for a detailed description of the construction and operation of these parts.

At the rear of the jack 4 is the slide 6 in which is mounted the bracket 7. The slide 6 is adjustable laterally by suitable means such as the hand-wheel 8 and toward and from the front of the machine by a hand-wheel 9 to properly position the bracket 7 and parts carried by it with relation to the shoe to be treated. The details of these parts and others forming features of the complete machine shown in the before-mentioned patent, are not herein illustrated and described, as such details are well understood by those skilled in the art and form no essential part of the present invention.

To support and straighten the projecting edge of the wedge and outersole as the heel portion of the shoe is subjected to pressure, the edge leveling means extends about the heel portion of the shoe and engages the top of the projecting edge of the wedge and to level the tread surface of the heel portion of the outersole the interior of the shoe

is engaged by means opposed to the tread surface leveling plate. These parts may be variously formed, but in the present instance of the invention, the edge leveling means comprise clamps which embrace the 70 exterior heel portion of the shoe and have substantially flat surfaces which engage the top surface of the projecting edge of the wedge. The means for supporting the interior of the shoe may be a jack having a 75 part to engage the inner surface of the innersole, or if the spring-heel shoe is to be leveled on the last, it may be formed by the last itself.

In the illustrated form of the invention, 80 the edge leveling member comprises a two-part clamp formed of the portions 10 having inner surfaces 11 adapted to contact with the counter or heel portion of the shoe upper and each provided with substantially 85 flat lower surfaces 12 to extend into the crease and engage the top of the exterior projecting portion of the wedge 13 which is interposed between the outersole 14 and the innersole 15.

The two parts 10 of the edge leveling member are carried by a block 16 from which projects a pin 17. The pin 17 passes through an adjusting device 18 threaded into the bracket 7, substantially as indicated 95 in Figs. 1 and 2, and whereby the edge leveling member may be appropriately adjusted toward and from the front of the machine for accommodating different kinds of shoes.

In order that the edge leveling member 100 may be adjusted to the treatment of shoes of different sizes and yet present a substantially continuous flat leveling surface for engaging the top of the projecting portions of the wedge, the portions 10 are pivotally 105 connected to the block 16 as by means of the pivot stud 19, and the adjoining edges of the portions 10 are overlapped as indicated at 20, Fig. 3.

Extending laterally from the bracket 7 110 are the guideways 21 in which are mounted the arms 22. The arms 22 are connected by the links 23 to the portions 10 of the edge leveling member, substantially as indicated in Fig. 1.

In order that the edge leveling member 115 may be properly adjusted to different sizes of shoes, the arms 22 are connected by the right and left screw-threaded adjusting device 24 held between the end portions of 120 the bracket 25 secured to one of the guideways 21 and provided with a hand-piece 26, the construction being such that upon manipulation of the hand-piece 26 the right and left threaded device 24 may be turned 125 to move the arms 22 and, perforce, the portions 10 of the edge leveling member into proper width relation to accommodate the particular shoe to be treated.

In the illustrated form of the invention, 130

the shoe is supported upon the jack 4 which, as hereinbefore noted, may either be provided with means for engaging the last pin socket of the last within the shoe, or be provided with a part to engage the inner surface of the innersole, according as the shoe is to be leveled on or off the last.

5 The tread surface leveling member is provided with a suitable flat surface for engaging the heel portion of the outersole, the construction being such that upon relative movement of the said member and the opposed shoe supporting members toward each other, the edge portions of the wedge and 10 outersole about the heel will be straightened by the substantially flat surfaces 12 of the edge leveling member and the tread surface at the heel portion of the outersole will be flattened and made uniform.

15 20 In the illustrated form of the invention, where the leveling action is to be performed in the machine which drives the nails, the tread surface leveling member comprises a plate 27 which may be pivotally mounted to the nail block head 2, as by the pivot 28, and to lock the tread surface leveling member in operating relation with the opposed members, said leveling plate may be provided with an opening 29 for the reception of a 25 30 pin 30, the construction being such that by withdrawal of the pin 30, the tread surface leveling member 27 may be turned to one side, away from position above the nail block, to permit the nails to be driven, and 35 40 after they have been driven, be returned to operative position to effect the shoe leveling operation.

The tread surface leveling member 27 is 45 provided with an inclined portion 31 adapted to contact with the incline or break of the heel as the shoe is subjected to the leveling pressure, the construction being such that the incline 31 of the tread surface leveling plate straightens the incline and at the same time insures that the corner nails 32 be 50 55 properly clenched.

In order that the projecting edge of the wedge and outersole may be properly supported during the action of the incline 31 upon the break of the heel, the portions 10 50 of the edge leveling member are extended forwardly to or beyond the break of the heel, substantially as indicated in Fig. 1, so that when the incline portion 31 acts upon 55 the break of the heel to insure proper clenching of the corner nails 32, the wedge and outersole will be sustained against deflecting action and the lines of these parts be straightened and leveled.

60 65 From the incline 31, the tread surface leveling member may extend forwardly over the shank of the shoe, if desired, substantially to the ball line. This feature of the tread surface leveling member is indicated

at 33, Fig. 4, the construction being such 65 that while the projecting edge portions of the wedge and outersole are straightened about the heel portion of the shoe and the corner nails at the break of the heel are properly clenched, the shank portion of the 70 shoe is also subjected to the leveling action. In this aspect of the invention, if the shoe is being leveled off the last, the innersole engaging portion of the jack will extend forward commensurate with the forwardly-projecting portion 33 of the tread surface leveling member, or substantially to the ball line of the shoe.

75 When, as in the illustrated embodiment of the invention, spring-heel shoes are 80 leveled in the machine which also previously drives the nails, the two-part clamp may act to position the heel portion of the shoe for the nail driving operation while the substantially flat lower surface 12 of the edge 85 leveling member may enter the crease about the heel of the shoe and maintain the lines of the projecting edge of the wedge and outersole in proper position while the nails are 90 being driven.

95 The tread surface leveling member is 100 preferably formed as indicated in Fig. 4, wherein the flat surface for engaging the heel tread portion of the outersole is formed by a transverse recess 34 formed in the top portion of the leveling member, but as indicated in Fig. 6, this construction may be varied, if desired, and the leveling plate be provided with a recess 35 and incline 36 and shank-engaging portion 37, substantially in 105 conformation with the general outlines of the spring-heel shoe to be leveled.

110 In operation, a spring-heel shoe, the heel portion of which has been previously secured to the heel seat by metallic fastenings 105 or nails, is placed upon the jack or inner support for the shoe, the edge leveling member is adjusted to extend into the crease about the heel portion of the shoe with the flat surface of said member bearing upon 110 the top of the projecting edge of the wedge, and the portions of the shoe between the jack, the edge leveling member and the tread leveling member, are subjected to a leveling pressure which straightens the edge portions 115 of the wedge and outersole, levels the tread surface of the outersole engaged by the tread surface leveling member, and clenches the corner nails to securely hold the parts in permanent relation. Where the nails are 120 driven in the same machine wherein the leveling operation is effected, the shoe will have been placed upon the jack and the edge leveling member have been placed in the described position for the nail-driving operation, the tread surface leveling member at such times being swung to one side. In 125 such machine, it is only necessary in order

to effect the described leveling operation and straightening the lines of the wedge and outersole about the heel portion of the shoe, to swing the tread surface leveling member 5 into operative relation with the jack and the edge leveling member, and then subject the parts to leveling pressure.

What is claimed is:—

1. In a machine for leveling spring heel 10 shoes, the combination of a member having a surface to engage and support the top of the wedge and outersole uniformly from the bottom of the crease to the edge of the wedge and outersole about the exterior heel portion 15 of the shoe, and a tread surface engaging member to engage the tread surface of the outersole about the heel portion of the shoe, said members being relatively movable to subject the parts between them to a leveling 20 pressure to straighten the lines of the crease after the spring heel has been secured to the shoe.
2. In a machine for leveling spring heel 25 shoes after the sole and heel wedge have been secured thereto, the combination of opposed leveling pressure members, one of said members adapted to engage the tread surface of the outersole, and the other of said pressure members having substantially flat engaging 30 portions for supporting the top surface of the wedge from the bottom of the crease to the edge of the wedge about the exterior of the heel to flatten the lines of the crease as the parts between said members are subjected 35 to a leveling pressure.
3. In a machine of the class described, the combination of a pressure member for engaging the interior of the heel portion of a spring heel shoe, a leveling member having 40 a substantially flat leveling surface for engaging and supporting the top portion of the wedge uniformly from the bottom of the crease to the edge of the wedge about the heel of the shoe, and a leveling plate for engaging the tread surface of the outersole about the heel of the shoe opposite to said flat surface, said leveling members and plate being relatively movable to subject the spring heel between them to a leveling pressure 45 to flatten the edge of the wedge about the heel of the shoe, and straighten the lines of the crease after the spring heel has been nailed to the shoe.
4. In a machine of the class described, the 50 combination of means for engaging the interior of a spring heel shoe, means provided with a substantially flat surface for engaging the exterior top portion of the wedge from the bottom of the crease to the edge of the wedge and extending with substantial continuity about the heel part of the shoe to a point beyond the incline of the wedge, and a leveling member for engaging the heel tread portion of the outersole, said

two means and leveling member being relatively movable for subjecting the spring heel between them to a leveling pressure to straighten the edge of the wedge from the heel to the incline of the wedge and level the tread surface of the outersole after the heel 70 has been secured to the shoe.

5. In a machine of the class described, leveling means for a spring heel shoe, comprising, in combination, counter clamping members having flat lower overlapping surfaces 75 for uninterrupted engagement with the top of the wedge about the heel of the shoe to the end of the incline, and a leveling plate for engaging the tread surface of the outersole below said flat surfaces, said counter 80 clamp and leveling plate being relatively movable for subjecting a spring heel between them to a leveling pressure to straighten the projecting edges of the wedge and outersole about the heel of the shoe and leveling the 85 tread surface of the outersole.

6. In a machine of the class described, leveling means for a spring heel shoe, comprising, in combination, counter clamping members having flat lower overlapping surfaces 90 for uninterrupted engagement with the top of the wedge projecting about the heel of the shoe, said surfaces extending beyond the end of the wedge incline, means for adjusting said counter clamps and surfaces to accommodate spring heel shoes of different 95 sizes, and a leveling plate for engaging that portion of the tread surface of the outersole which is below said flat surfaces when the shoe is in leveling position, said counter 100 clamp and leveling plate being relatively movable for subjecting a spring heel between them to a leveling pressure to straighten the projecting edges of the wedge and outersole about the heel of the shoe and leveling the 105 tread surface of the outersole.

7. In a machine for leveling spring heel 110 shoes after the sole and heel wedge have been secured thereto, the combination of a support for sustaining the interior of the shoe for a leveling pressure, means exterior of the shoe provided with a flat lower surface for engaging the top of the wedge from the bottom of the crease to the edge of the wedge about the heel of the shoe and to a 115 point beyond the incline of the wedge, and a leveling plate for engaging the tread surface of the outersole opposite said flat surface when the shoe is in leveling position.

8. In a machine of the character described, 120 the combination of a member having a substantially flat surface to engage the top of the wedge of a spring heel shoe, an opposed nail block, a leveling plate mounted for movement to and from operative position 125 over the nail block and having a leveling portion opposed to the said flat surface when in operative position, and means for locking

the leveling plate in operative position, said member and leveling plate being relatively movable for subjecting a spring heel between them to a leveling pressure to 5 straighten the lines of the crease.

9. In a machine of the class described, spring heel leveling means, comprising, in combination, clamps for engaging the counter of the shoe, means for adjusting the 10 clamps for shoes of different size, said clamps having overlapping portions to provide a continuous engaging leveling surface for the top of the wedge projecting about the heel of the shoe, and a leveling plate for engaging the tread surface of the outersole 15 below said engaging surface for straightening the lines of the crease as said clamps and leveling plate are relatively moved after the heel has been attached to the shoe.

10. In a machine of the class described, the combination of a member having a surface to engage the top of the wedge projecting about the heel of a spring heel shoe, a leveling plate pivotally mounted to swing to 25 and from opposed relation with respect to said surface, and means for locking the leveling plate in operative position, said member and plate being relatively movable for subjecting a spring heel between them to 30 pressure to straighten the lines of the crease.

11. In a machine for nailing and leveling the heel portions of spring heel shoes, the combination of a nail block and opposed pressure member, a spring heel leveling plate

mounted for movement to and from operative position over the nail block and having an inclined portion opposed to the break of the heel when in operative position, and an edge supporting member in opposed relation to the nail block and having a substantially 40 flat surface opposite pressure exerting portions of the leveling plate when in operative position and extending about the heel to a point beyond the incline of the wedge to directly support the edge of the wedge 45 throughout its contour and a portion of the edge of the outersole beyond the incline of the wedge when the leveling pressure is applied.

12. In a machine for leveling the heel portions of spring heel shoes after the fastenings have been driven, the combination of a nail block, an opposed pressure member having a substantially flat surface for engaging the edge portion of the wedge and extending to a point beyond the incline of the wedge, and a leveling plate having a portion 55 opposed to the flat surfaces of the pressure member to subject the projecting edge of the wedge and sole to a leveling pressure and 60 mounted to swing to and from operative position over the nail block, said leveling plate having an inclined portion opposed to the break of the heel.

In testimony whereof I have signed my 65 name to this specification.

DANIEL M. FRYE, JR.
